UNITED STATES PATENT OFFICE.

EDWARD POSSON, OF CHICAGO, ILLINOIS.

CAR-TRUCK.

1,348,124.

Specification of Letters Patent. Patented July 27, 1920.

Application filed July 6, 1917. Serial No. 178,890.

To all whom it may concern:

Be it known that I, EDWARD POSSON, a citizen of the United States, residing at Chicago, in the county of Cook and State of

5 Illinois, have invented certain new and useful Improvements in Car-Trucks, of which the following is a specification.

This invention relates to an improvement in car trucks and in particular to an improvement in the construction of the side frames of car trucks, whereby a stronger, more rigid, and more durable construction is secured. In car trucks of the general type now in use in freight cars, the truck bolster 10 passes through between the column castings, and the latter members are connected to the arch bars by means of the usual column bolts only, so that in operation an undue stress is placed upon these bolts resulting in 15 the weakening or breakage of the bolts and other parts of the side frame structure. For instance, when the brakes are set on a car coming down grade, the truck is held back and the bolster bears against the forward 20 column so that the entire pressure is transmitted to the column bolts, causing them to bend backward and causing the top end of the column castings to break out. Furthermore the constant jerking which takes place 25 through the train, the unevenness of the track and other like causes, operate to effect a constant pounding of the truck bolster against the top of the column castings.

The principal object of the present invention is to overcome the above-mentioned difficulty by providing an improved car truck construction in which the column castings are supported by other members in addition to the usual column bolts. A further feature 30 is the provision of means for tying together and mutually supporting the column castings whereby stress imparted to one of the castings will be transmitted to the other and thereby distributed to the side frame. A further feature is the provision of a connecting member for uniting the upper ends of the column castings independently of the upper arch bar. A further feature is the provision of means whereby the improvement in 40 the mounting of the column castings may be embodied in substantially any car truck

without reforming the upper arch bar. Other objects relate to various features of construction and arrangement which will appear more fully hereinafter.

55

In the drawings,

Figure 1 shows a side elevation of a car truck embodying the features of the present invention;

Fig. 2 shows a reduced side elevation of the side frame of a car truck embodying the present invention;

Fig. 3 shows an enlarged side elevation of the upper end of one of the column castings showing the means for mounting the improved tie bar thereon;

Fig. 4 shows an enlarged vertical section taken longitudinally of the car through the column casting opposite the one illustrated in Fig. 3;

Fig. 5 shows a top plan view of the structure illustrated in Fig. 3;

Fig. 6 shows a top plan view of the structure illustrated in Fig. 4; and

Fig. 7 shows an enlarged vertical section taken transversely of the car on the line 7-7 of Fig. 5.

In the drawings I have illustrated in Fig. 1 a car truck comprising an upper arch bar 10, a lower or inverted arch bar 11, and a pedestal tie-bar 12, which are arranged in the usual manner, as shown. The ends 10^a of the upper arch bar are disposed adjacent and parallel to the ends 11^a of the lower arch bar, and the usual journal boxes 13 are 80 adapted to be mounted between the ends 10^a of the lower arch bar and the ends of the pedestal tie-bar 12, being secured in position by means of the journal box bolts 14. The car wheels 15 have their axles journaled in 85 the boxes 13. The side columns or column castings 16 extend vertically between the central part 10^b of the upper arch bar and the lower central part of the inverted arch bar 11, these parts being normally secured in 90 adjusted position by means of the column bolts 17, which are engaged at their lower ends by the nuts 18. The lower arch bar carries a bolster spring seat 19 having mounted thereon the bolster springs 20 carrying the spring plate 21, upon which is seated the truck bolster 22, which projects 95 100

between the side columns 16. The side columns are provided with brake hanger carriers 23 which are connected by pins 24 with the brake hangers 25 by which the brake shoes 26 are carried. These features are parts of a usual car truck construction and are illustrated and described as a basis for explaining the improvement which constitutes the present invention.

- 10 In order to prevent the bending and weakening of the column bolts 17 and the breakage or injury to the upper parts of the columns 16, I have provided a tie-bar 30 which lies between the horizontal part 10^b of the upper arch bar and the upper ends of the column 16, as shown in Figs. 1 and 2. This tie-bar is provided at its ends with downwardly directed lugs or hooks 31, which engage the outside walls of the column 16, so that relative spreading of the upper ends of the columns longitudinally of the car is prevented. This tie-bar 30 lies between the upwardly directed flanges 32 and the upper ends of the columns 16, as shown particularly in Figs. 3 to 7, inclusive, so that movement of the tie-bar transversely of the car is prevented, and, at the same time, the tie-bar is held against vertical movement by means of the column bolts 17 which pass downwardly through the upper arch bar, through the tie-bar, and downwardly through the column 16. The rotation of the column bolt 17 is prevented by means of metal clips or plates 33 having flanges 33^a extending over one side of the upper arch bar and having ears 33^b which may be bent upwardly to engage one of the flat sides of the square heads of the bolts. In this way the tie-bar 30 is held securely in position, and the pounding stresses which are received by the column castings 16 from the truck bolster are transmitted from one column casting to the other and thus transmitted again to the truck bolster and other parts of the side frame construction, so that the stress upon the column bolts is relieved, and whatever stress is imparted thereto is divided between the two column bolts of each side frame.
- 50 The use of the tie-bar 30, in connection with an old car truck or one which has been designed according to previous standards, results in the upward spacing of the upper arch bar 10 from its normal position, and 55 in order to make it possible to apply this invention to substantially any of the car trucks now in use, I have provided filler plates 35 which may be interposed between the ends 10^a and 11^a of the upper and lower 60 arch bars, respectively, so that these parts may be spaced apart the same distance vertically that the central part of the upper arch bar is spaced from the upper ends of the side columns 16 by the interposition of 65 the tie-bar 30.

Although I have shown and described a particular embodiment of this invention for purposes of illustration, it will be understood that it may be embodied in various different forms without departing from the 70 spirit of my invention as defined in the appended claims.

What I claim is:

1. In a car truck, a side frame comprising upper and lower arch bars and side columns extending between said arch bars, spacing plates inserted between adjacent ends of said arch bars and between the ends of said side columns and said upper arch bar, means carried by one of said plates to prevent spreading of said side columns, and means for securing said parts together. 75

2. In a car truck, a side frame comprising an upper arch bar and side columns, a truck bolster extending between said columns, a tie-bar mounted between the ends of said columns and said arch bar for uniting said columns, means for supporting the ends of said arch bar, and spacing plates inserted 80 between said supporting means and said ends of said arch bar. 85

3. In a car truck, a side frame comprising an upper arch bar and side columns, a tie-bar interposed between the upper ends of said side columns and said arch bar, the upper ends of said side columns being recessed to receive said tie-bar, lugs projecting downwardly on the opposite ends of said tie bar to engage said side columns, column bolts 100 for securing said members together, and a truck bolster extending between said side columns. 95

4. In a car truck, an upper arch bar, a lower arch bar, side columns mounted between said arch bars, column bolts for uniting said members, a truck bolster extending between said columns, and a tie-bar interposed between the upper ends of said side columns and said upper arch bar, said tie-bar having lugs engaging the outer sides of said side columns, said side columns having upwardly extending flanges located on opposite sides of said tie-bar. 105

5. In a car truck, an upper arch bar, a lower arch bar, side columns mounted between said arch bars, column bolts for uniting said members, a truck bolster extending between said columns, and a tie-bar interposed between the upper ends of said side columns and said upper arch bar, said tie-bar having lugs engaging the outer sides of said side columns, said side columns having upwardly extending flanges located on opposite sides of said tie-bar, said tie-bar being 110 provided with apertures through which said column bolts extend. 120

6. In a car truck, an upper arch bar, a lower arch bar, side columns mounted between said arch bars, column bolts for unit- 130

ing said members, a truck bolster extending between said columns, a tie-bar interposed between the upper ends of said side columns and said upper arch bar, said tie-bar having 5 lugs engaging the outer sides of said side columns, said side columns having upwardly extending flanges located on opposite sides

of said tie-bar, and spacing plates inserted between the ends of said upper arch bar and the ends of said lower arch bar. 10

In testimony whereof, I have subscribed my name.

EDWARD POSSON.
